UNITED STATES PATENT OFFICE.

FRANK B. GILLIGAN, OF NEW YORK, N. Y.

PULP AGITATOR AND REFINER.

1,127,615.

Specification of Letters Patent.

Patented Feb. 9, 1915.

Application filed May 5, 1914. Serial No. 836,579.

To all whom it may concern:

Be it known that I, FRANK B. GILLIGAN, a citizen of the United States, and resident of the borough of Brooklyn, county of 5 Kings, city and State of New York, have made a certain new and useful Invention Relating to Pulp Agitators and Refiners, of which the following is a specification, taken in connection with the accompanying drawing, which forms part of the same.

This invention relates especially to agitators and refiners for paper pulp or similar fibrous material in which the tank is provided with a circulating system comprising 15 an uptake pressure pipe so as to discharge the pulp or fibrous material at relatively high pressure and velocity against a suitable impact member which may be provided with separating projections or serrations to 20 promote the disintegration or separation of the fibrous material.

In the accompanying drawings showing in a somewhat diagrammatic way an illustrative embodiment of this invention, Fig. 25 ure 1 is a vertical section, parts being shown in elevation; and Fig. 2 is a bottom view taken substantially along the line 2—2 of Fig. 1.

The tank 1 may be of any suitable size 30 and construction and may be mounted on suitable supports, such as 9. The tank is preferably provided with an inclined discharging bottom such as 4 so as to promote the discharge of the suspended fibrous material through the opening 3. The circulating pump or pressure device may be a suitable centrifugal pump, such as 7, preferably having a central top delivery which may with advantage be brought into substantial 35 vertical alignment with the uptake pressure pipe 2 and be connected therewith through a suitable control valve, such as 10. The inlet connection of the pump, such as 5, may be substantially straight in its upper 40 portion at least and aligned with the discharge opening 3 of the tank, a suitable shut-off valve such as 6 being interposed in this connection, if desired. This circulating pump is arranged so as to create different 45 pressures for the different treatments desired and this may be accomplished by throttling the control or shut-off valves referred to or by varying the pump speed, or both, and as indicated the pump may be 50 driven by a belt co-operating with the step or cone pulley 8 and provided with a low

speed or pressure portion to be used when the tank is merely operating as a circulating or mixing tank in connection with washing or bleaching operations. A smaller 60 high speed and high pressure part of this pulley is adapted to give a considerably higher pressure or velocity to the material forced through the uptake pressure pipe so as to be more desirable when a stronger 65 disintegrating or refining action is required.

A suitable impact member is arranged to co-operate with the upper discharge end of the pressure pipe 2 and if desired this impact member may have a conical central 70 portion 23 so as to project more or less within the flaring pressure nozzle 20 and centrally engage the jet of material discharged therefrom. The impact member 18 may for this purpose be arranged substantially centrally above the pressure pipe and be vertically adjustable with respect thereto by providing it with a suitable adjusting screw 14 which may be turned by the adjusting lever 15 so as to adjust the vertical position of this impact member in connection with the threaded seat 17 in the upper frame members 16 secured at the top of the tank. It is desirable to provide the impact member with removable impact 75 plates throughout at least part of its surface and for this purpose the sectional impact plates 11 may be used and secured to the impact member 18 in any desired way so as to be readily renewed when worn. For 80 many purposes projections or serrations are desirable on the impact surfaces and these may be conveniently formed in the stamped or otherwise shaped impact plates of sheet steel or the like which may be provided with V-shaped teeth or projections, such as 19, so as to exert the desired separating or 85 disintegrating action on the fibrous material during the refining thereof.

The charge of suspended paper pulp or 90 other fibrous material or the like may be supplied to the tank through the supply pipe 21, located at any convenient point and provided with the valve 22. When the tank has been filled to the desired extent, preferably up to about the upper end of the uptake pressure pipe 2 the circulating pump 95 may be started and the material forced with the desired pressure or velocity up through the pressure pipe and into impingement 100 with the impact member which may be vertically adjusted so as to secure the desired 110

intensity of separating and disintegrating action. For instance, the impact member may be brought down into dotted position so as to considerably throttle the effective 5 opening of the pressure nozzle and develop the desired high pressure in the escaping jet at this point which for some purposes may be many pounds per square inch. The conical point of the impact member separates 10 and distributes the jet of material throughout the different parts of the tank and the material gradually descends down through the tank as indicated by the arrows. For less energetic action during mixing, washing or bleaching operations the impact member may be raised to a greater extent toward the upper position indicated in full lines in the drawing when its spreading action is of relatively greater importance. 15 When the desired treatment of the charge has been effected it may be withdrawn from the tank by more or less closing the control valve 10 and opening the discharge valve 13 so as to allow the material 20 to be discharged from the discharge pipe or connection 12, more or less circulation being preferably maintained up through the tank at the same time if settling is to be minimized. 25 This invention has been described in connection with a number of illustrative embodiments, forms, arrangements, materials, proportions and operations of parts, to the 30 details of which disclosure the invention is not of course to be limited, since

What is claimed as new and what is desired to be secured by Letters Patent is set forth in the appended claims.

1. In agitators and refiners for paper pulp 40 and similar fibrous material, a tank provided with an inclined bottom discharge, a

substantially central valved uptake pressure pipe arranged in said tank and provided with a flaring pressure nozzle, an adjustable pressure centrifugal pump having a central 45 top delivery connected to said pressure pipe, a valved substantially vertical inlet connection from the discharge of said tank to said pump, a vertically adjustable substantially conical impact member arranged substantially axially in the upper portion of said tank to coöperate with the discharge end of said pressure pipe to refine and substantially uniformly distribute the material 50 throughout said tank, replaceable impact 55 plates secured on said impact member and provided with disintegrating serrations and a valved discharge pipe connected to the delivery of said pump.

2. In agitators and refiners for paper pulp 60 and similar fibrous material, a tank provided with an inclined bottom discharge, a substantially central valved uptake pressure pipe arranged in said tank and provided with a flaring pressure nozzle, an adjustable 65 pressure centrifugal pump having a top delivery connected to said pressure pipe, a valved substantially vertical inlet connection from the discharge of said tank to said pump, a substantially conical impact member 70 arranged substantially axially in the upper portion of said tank to coöperate with the discharge end of said pressure pipe to refine and substantially uniformly distribute the material throughout said tank, and a valved discharge pipe connected to the 75 delivery of said pump.
